UNITED STATES PATENT OFFICE.

JAMES M. DODDRIDGE, OF MILTON, AND JOHN C. BECK, OF INDIANAPOLIS, INDIANA.

DETACHABLE CASKET-HANDLE.

1,106,031.

Specification of Letters Patent.

Patented Aug. 4, 1914.

Application filed December 26, 1911. Serial No. 667,897.

To all whom it may concern:

Be it known that we, JAMES M. DODDRIDGE and JOHN C. BECK, citizens of the United States, residing at Milton, in the county of Wayne, and at Indianapolis, in the county of Marion, respectively, and State of Indiana, have invented a new and useful Detachable Casket-Handle, of which the following is a specification, reference being had 10 to the accompanying drawings and to the letters and figures of reference marked thereon.

This invention relates to portable casings or boxes, especially to burial caskets or coffins, the invention having reference more particularly to detachable handles therefor.

The primary object of the invention is to provide improved detachable handles and connections therefor that shall be so constructed as to be especially adapted for use on coffins or the like and adapted to be quickly removed; a further object being to provide simple and relatively inexpensive removable handles and connections therefor 25 which will permit customers to select a suitable style of coffin or casket with inexpensive attachments to which any one of the different styles of handles preferred may be detachably connected, a still further object 30 being to provide burial caskets at a relatively small cost without permanent handles and permitting the funeral director to loan the handles to the purchaser of the casket until the conclusion of the burial ceremonies.

The invention consists in an inclosing receptacle having a plurality of holding devices permanently secured thereto and adapted to removably secure handle-frames to the receptacle, the handle-frames having 40 suitable handles connected thereto; and the invention consists further in novel holding devices and in novel handle-frames, and also in the parts and combinations and arrangements of parts as hereinafter particularly 45 described and pointed out in the accompanying claims.

Referring to the drawings, Figure 1 is a perspective view of a burial casket or coffin provided with the improved detachable handles; Fig. 2, a fragmentary vertical section approximately on the line A A in Fig. 1; Fig. 3, a vertical section as on the line B B in Fig. 2; Fig. 4, a fragmentary vertical section approximately on the line C C

in Fig. 3; Fig. 5, a rear perspective view of 55 the improved handle-frame, and Fig. 6, a fragmentary perspective view showing a portion of the casket to which one of the handle-frame holders is connected.

Similar reference characters throughout 60 the drawings indicate corresponding elements or features of construction herein referred to.

The casket or receptacle may be variously constructed in detail and the sides 1 thereof 65 are each provided with a suitable number of handles for conveniently carrying the casket, and the handles 2, 2', may be of any suitable or desired design, the handles being suitably connected to handle-frames 3, 3', respectively. Preferably the handles are designed 70 to drop when not in use, the frames being provided with pivoting ears 4, 4', and each handle has two arms 5 and 5' that are connected to the ears by means of pivots 6 and 75 6' respectively. The handle-frames may be composed either of pressed plate metal or of cast metal and in any suitable design. The rear side of each frame 3, 3', has two guide bars 7 and 8 thereon that are suitably spaced 80 apart and arranged parallel one to another, and they extend horizontally and are nearly as long as the frame in horizontal direction. The frame 3 is suitably dished so that the edge portion thereof forms a flange-like 85 rearward extension or bearing flange 9 adapted to serve as a base in contact with the side 1 of the casket. The guide bar 7 has a flange-like lug, or preferably two lugs 10 and 11 thereon that extend toward the 90 companion guide bar 8, the lugs being suitably spaced apart so as to leave a gap between them, one lug being arranged at a suitable distance from one end of the guide bar and the other lug extending from the 95 opposite end of the guide bar. The guide bar 8 has also a flange-like lug, or preferably two lugs 12 and 13 extending toward the lugs 10 and 11, being arranged oppositely thereto. The guide bar 7 has a stop bar 14 100 connected to the end thereof from which the lug 11 extends and the stop bar is connected also to the end of the lug, a similar stop bar 15 being arranged oppositely to the stop bar 14 and connected to the guide bar 8 and the 105 lug 13, said stop bars being fixedly connected also to the rear side of the frame 3. The middle portion of the frame preferably has

a set-screw 16 inserted therein so as to extend rearwardly, the outer or forward end of the set-screw being provided with a knurled head 17.

5 In order to detachably connect each handle-frame to the casket or box the sides 1 are provided with a suitable number of permanently secured holders, which, however, may be detached if desired, each holder comprising 10 a base plate 18 which is secured to the side of the casket preferably by means of screws 19, 19', the plate having two guide bars 20 and 21 thereon that extend forwardly and are parallel one to another, being spaced a suitable distance apart so as to enter between the ends of the lugs of the oppositely arranged guide bars 7 and 8. The guide bar 20 as preferably constructed has two flange-like lugs 22 and 23 thereon 15 that extend upwardly from the guide bar, and the guide bar 21 has two lugs 24 and 25 thereon that extend downwardly parallel to the plane of the base plate 18. The lugs 22 and 23 are adapted to be engaged by the lugs 10 and 11 respectively, the lugs 24 and 25 being adapted to be engaged by the lugs 12 and 13 respectively, while the frame is guided by means of the guide bars 7 and 8 in contact with the guide bars 20 and 21 respectively, for holding the bearing flange 9 of the frame in contact with the side of the casket. The frame is prevented from being accidentally moved horizontally by means of the set-screw 16.

35 It should be understood that in some cases, especially if a relatively small handle-frame is preferred, the lugs 11 and 13 may be omitted from the guide bars 7 and 8 respectively, in which case the lugs 23 and 25 40 may be omitted from the guide bars 20 and 21 respectively.

It should be understood that the improved handle-frames and holders therefor are to be used not only with coffins or caskets but 45 also with the inclosing boxes in which the caskets or coffins are placed in graves.

In practical use the handle frame 3 is placed at the front of the base plate 18 and the guide bars 7 and 8 are then moved into 50 contact with the ends of the lugs on the base plate 18, the frame being somewhat at one side of its normal position so that the lug 10 may pass between the lugs 22 and 23 and the lug 12 pass between the lugs 24 and 25, 55 and when the frame is moved back to the side of the casket the frame may be moved longitudinally so that the respective lugs are brought into engagement as herein-before specified, and then the set-screw 16 may, if 60 desired, be forced into contact with the base plate 18 for securely holding the frame with the lugs 22 and 24 in contact with the stop bars 14 and 15 respectively. The lugs of the frame coöperating with the lugs on the base 65 plate 18 enables the handle-frames to lift

the casket. When it is desired to remove the handles the set-screws 16 are slightly slackened and then the handle-frames are moved horizontally until released from the holders, and are then easily removed from the casket. 70

Having thus described the invention, what is claimed as new is—

1. A handle frame comprising a plate having a continuous bearing flange, and two oppositely arranged guide bars secured to 75 the plate within the confines of the flange, each bar having a lug thereon extending toward the lug of the opposite one of the bars, for connection with and inclosing a holder having a pair of lugs. 80

2. A handle frame comprising a plate having a bearing flange, and two guide bars secured to the plate within the confines of the flange, each bar having two lugs spaced apart thereon and extending toward the lugs 85 of the remaining one of the bars, one of the two lugs being arranged at a distance from one end of the bar and the other lug extending from the opposite end of the bar, for connection with and inclosing a holder having two pairs of lugs. 90

3. A detachable handle comprising a base plate, having two guide bars thereon provided each with a lug, a frame having two guide bars thereon provided each with a lug, the lugs of the guide bars that are on the frame being detachably connected with the lugs of the guide bars that are on the base plate, a set-screw inserted in the frame and seated against the base plate, and a handle 100 on the frame. 95

4. In a burial casket handle, the combination with a handle of a handle holder comprising a normally upright base plate having two horizontally extending guide bars 105 thereon that extend also outwardly in parallel order, one guide bar above the other, the uppermost one of the guide bars having two upwardly extending lugs thereon, the lower bar having two downwardly extending lugs thereon, a frame connected to the handle and having two guide bars thereon, extending oppositely above and below the upper and lower guide bars of the base respectively and having lugs thereon engaging 115 the aforementioned lugs, said frame having stop-bars thereon engaging one of the lugs of each of the guide bars that are on the base plate, and a set-screw inserted in the frame and seated against said base plate. 120

5. A detachable casket handle comprising a base plate having two longitudinally extending parallel guide bars thereon, each guide bar having two lugs spaced apart thereon that extend outward away from the 125 lugs of the opposite bar, a frame having two longitudinally extending parallel guide bars on the back thereof having each two inwardly extending lugs spaced apart thereon engaging the aforementioned lugs and re- 130

movably connecting the frame to the base plate, the frame having a stop bar thereon engaging one of the lugs of one of the guide bars that are on the base plate, the frame
5 having also an inclosing flange extending about all the guide bars, and a handle connected to said frame.

In testimony whereof, we affix our signatures in presence of two witnesses.

JAMES M. DODDRIDGE.
JOHN C. BECK.
